CLAIM

The ornamental design for a dispenser case for a contact lens cleaning fabric, substantially as shown and described.

DESCRIPTION

FIG. 1 is a front isometric view of a dispenser case for contact lens cleaning fabric showing my new design;
FIG. 2 is a rear isometric view thereof; the bottom being unornamented;

FIG. 3 is a top plan view thereof;

FIG. 4 is a left end elevational view thereof;

FIG. 5 is a right end elevational view thereof.

FIG. 1

FIG. 2

FIG. 3

FIG. 4

FIG. 5
